REGISTER TOP PLATE.

1,117,568.

Specification of Letters Patent.

Patented Nov. 17, 1914.

Application filed May 12, 1914. Serial No. 837,999.

To all whom it may concern:

Be it known that I, HOWARD S. HART, a citizen of the United States, residing at New Britain, Hartford county, State of Connecticut, have invented certain new and useful Improvements in Register Top Plates, of which the following is a full, clear, and exact description.

My invention relates to a perforated top plate for registers, ventilators and the like, the main object being to improve the same as to strength and efficiency.

In the accompanying drawings, Figure 1 is a top plan view of one corner of my improved top plate as it would appear in place. Fig. 2 is a view of the under side of said plate. Fig. 3 is a section on the line 3—3 of Fig. 1. Fig. 4 is a section on the line 4—4 of Fig. 1. Fig. 5 is a section on the line 5—5 of Fig. 1. Fig. 6 is a section on the plane of the line 4—4 showing a modification.

The plate is made from sheet metal and may be of any suitable outline, although preferably it is of rectangular form. The plate is perforated to provide a multitude of air passages for heating or ventilating purposes. In order to secure the greatest efficiency, it is essential that the air passages shall be as large as possible without unduly weakening the web, or perforated part of, the body. In the most highly developed form, the air passages should be rectangular or parallel sided except at the corners, which latter are rounded.

1 represents the border portion of my improved top plate, the central part being perforated as shown so as to provide bars running lengthwise and cross wise of said plate. The perforations may be formed by powerful presses or dies which cut away a portion of the metal and which deform the remaining bars or grids so as to bend them into the shape shown in Fig. 4, in which 2—2 represent said bars in section and 3 represents the side of one of the bars running transversely to the bars 2—2.

It will be observed that the bending of the metal is carried to such an extent as to force the two sides of each bar into contact, that is to say, the two sides are pressed together at the lower edge of each bar for the greater portion of the length of each of said bars. As shown, the down turned sides do not engage at the junction points of the cross bars 2—2 and 3—3 where, as seen in Fig. 2, there

are small pockets or cavities 4—4, each pocket being bordered by inwardly curved down turned walls 5—5 which are integral with down turned walls of the adjacent radiating bars. The walls 5—5 serve to bridge the corners and since they are integral with the side walls of the bars, they constitute a powerful reinforcing means at all junction points.

Since in registers and ventilators it is highly important to provide a maximum space or passage for the air, it is apparent from the foregoing that the total area of the air passage reaches its maximum by forcing the side walls of the grids or bars into engagement as shown. In order to reduce the danger of breaking the metal at the bend in the forming of the plate, it is preferable that the side walls do not engage each other flatwise throughout, but merely at the lower edges, as best seen in Fig. 4, there being a very slight cavity left directly under the curve of the arc, as shown. By my improvement, there is very little space afforded for the accumulation of dust or dirt. In some instances it may be desirable to reinforce one or more of the cross bars and to that end I may provide the modification shown in Fig. 6, in which 6 is a reinforcing bar or brace placed on edge, one edge of said reinforcing brace 6 projecting into a channel on the under side of the cross bar 2^a, the side walls of which, instead of being brought together at the lower edge are closed down on to the sides of the brace 6 as shown. Such a modification is desirable in the case of large register plates used for floor registers where in the plate should have a powerful load carrying capacity. Said reinforcements 6 may of course be used only at such intervals as the occasion requires, which would be determined largely by the thickness of the sheet metal used and the weight that the plate is designed to support.

It will be observed that all the cross bars between the junction points are arched, or in the form of an inverted U-shaped cross-section, with the lower edges pressed into contact. By pressing the edges into contact as shown, it will be apparent that the danger of buckling is avoided to a large extent (even when comparatively thin metal is used) since the contacting side walls tend to reinforce and support one another.

In the preferred construction as shown 110

22
 herein, all of the bars are arranged in alignment, that is to say, the bars running lengthwise of the plate are arranged in line and the bars running transversely are also arranged in line, although I do not wish to limit myself to this specific arrangement in all cases.

While I have shown my improved top plate in its perforated form, some changes and modifications may be made without departing from the spirit and scope of the invention.

What I claim is:

1. A sheet metal top plate for registers, 15 ventilators and the like, comprising a plate having a border portion and a perforated central portion forming cross bars between said perforations extending from border to border in both directions, said bars being 20 arched in cross-section, the lower part of the sides of said bars being closed together.
2. A sheet metal top plate for registers, 25 ventilators and the like, comprising a plate having a border portion and a perforated central portion forming cross bars between said perforations extending from border to border in both directions, said bars being arched in cross-section, the lower part of the sides of said bars being closed together, ex-

cepting at the junction points of said cross bars, inwardly curved depending walls at the border of said junction points, said walls being integral with the side walls of the adjacent bars radiating therefrom.

3. A sheet metal top plate for registers, 35 ventilators and the like, comprising a plate having a border portion and a perforated central portion forming cross bars between said perforations extending from border to border in both directions, said bars being 40 arched in cross-section, the lower part of the sides of said bars being closed together, the side walls of each bar being slightly separated adjacent to the inner wall at the top of the arch.

4. A sheet metal top plate for registers, 45 ventilators and the like, comprising a plate having a border portion and a perforated central portion, cross bars of arched cross section between said perforations extending 50 from border to border in both directions, the sides of a plurality of said bars being pressed together to afford mutual support against buckling and to provide maximum air space.
